UNITED STATES PATENT OFFICE

WILLIAM C. H. PETERS, OF ALBERT CITY, IOWA

SANITARY WELL TOP

Application filed November 9, 1931. Serial No. 573,799.

The object of my invention is to provide a sanitary well top of simple, durable and inexpensive construction, and which may be formed complete of two pieces of cast metal, 5 and readily and easily assembled and fitted to a well top and pump with a minimum of labor, and when so fitted it will provide a water and dust tight well top.

My invention consists in the construction, 10 arrangement and combination of the various parts of the device, whereby the objects contemplated are attained, as hereinafter more fully set forth, pointed out in my claim, and illustrated in the accompanying drawing, in 15 which:

Figure 1 shows a side elevation of my improved well top with a pump fitted thereto.

Figure 2 shows a top or plan view on an enlarged scale showing my improved well 20 top, a portion being broken away to show structural details.

Figure 3 shows an edge elevation of same illustrating the water and dust tight locking connection between the two sections.

Figure 4 shows a detail sectional view on the line 4—4 of Figure 2, the position of the bolt and the pump base being indicated by 25 dotted lines.

Figure 5 shows a sectional view on the line 30 5—5 of Figure 2; and

Figure 6 shows a sectional view on the line 6—6 of Figure 2.

Referring to the accompanying drawing, I have used the reference numeral 10 to indicate generally a pump of ordinary construction, the shape of a portion of its base being indicated by dotted lines in Figure 4.

My improved well top is preferably formed of cast metal complete in two parts. 40 Each part has at its central portion a raised flat pump supporting base indicated generally by the numeral 11, and preferably semi-circular in outline. A raised circular rib 11a surrounds the inner edge of said part 11.

45 From this base the outwardly extended sides of the well top are inclined downwardly and outwardly at 12, and may be provided with bolt openings 13 for securing it to a cement coping 14 surrounding the top of a well. One of the sections is provided on its

edge adjacent to the other section with an upwardly extending rib 15, extended from the flat pump base portion 11 downwardly and outwardly to the outer edge of the section. 55

The opposite section is provided at its edge adjacent to the first section with an inverted U-shaped rib 16 to overlap the rib 15 as clearly shown in Figure 3, and to lock the two sections firmly together against lateral 60 movement and at the same time provide a water and dust tight joint.

At the raised flat pump base supporting portion 11, the adjacent edges of the sections are provided with overlapping flanges 17, 65 shown in Figure 6.

To provide for bolting a pump to my improved well top I have formed in the portion 11 a series of grooves 18 to receive bolt heads, and these grooves have slots 19 extending upwardly through the well top. On the downwardly and outwardly inclined portions 12 these grooves 18 extend outwardly with their bottoms substantially horizontal, 70 so that any water that flows into the groove will discharge outwardly upon the inclined portion 12, and these outer ends are widened 75 so that the bolt head may readily be inserted therein.

On the under surface of my improved well top, I preferably provide a number of reinforcing ribs 20, and they preferably extend radially as shown in Figure 4.

In practical use with my improved well top it is obvious that the entire device may be formed complete of two sections of cast metal, and they do not need any grinding or machine work so that the expense of their manufacture is relatively small. 85

In assembling my well top, it is necessary to first place the section containing the rib 15 in position, and then the section containing the inverted U-shaped groove 16 in position with the rib 15 in the groove 16. 90 Then if necessary bolts may be inserted through the openings 13 to hold the well top down firmly against the well coping. Then the pump is placed in position and bolts are placed with their heads in the grooves 18, 95 and are extended upwardly therefrom. 100

Then the pump is placed in position with the bolts extending through the pump flange and the nuts are then tightened on top and the device is firmly and securely held in position against movement in all directions.

Obviously, the well top is completely sanitary because water and dirt cannot enter, and obviously any water or dirt that might enter under the pump base would be prevented from entering the well on account of the raised rib 11a.

I claim as my invention:

A sanitary well top formed complete in two sections, each section being formed with a raised pump seat portion at the center of its inner edge, the remainder of each section having its top surface inclined downwardly and outwardly, an upwardly extended rib formed on the inner edge of one of the sections and extending from the raised central portion to the outer end, the other section being formed on its inner edge with an inverted U-shaped rib shaped to receive said upwardly extended rib, and to thereby form a leak proof joint and at the same time securely lock the two sections together against movement away from each other.

Des Moines, Iowa, October 12, 1931.
